[57] CLAIM

The ornamental design for a combined camera dolly and support column therefor, as shown.

DESCRIPTION

FIG. 1 is a top, front and left side perspective view of a combined camera dolly and support column therefor showing my new design;

FIG. 2 is a left side view thereof;

FIG. 3 is a right side view thereof;

FIG. 4 is a front view thereof;

FIG. 5 is a rear view thereof;

FIG. 6 is an enlarged top view thereof;

FIG. 7 is a bottom view thereof;

FIG. 8 top view thereof, taken along line 8—8 of FIG. 2 with the steering wheel removed for clarity of illustration; and,

FIG. 9 is a reduced top, front and left side perspective view thereof with the camera support column in a collapsed position.
